Warren S. Ostow

ATTORNEY

UNITED STATES PATENT OFFICE.

RALPH W. ARMSTRONG, OF WESTFIELD, NEW JERSEY, ASSIGNOR OF TWO-THIRDS TO ARTHUR WATERMAN, OF EAST ORANGE, NEW JERSEY.

CLOTH CLIP.

1,417,129.

Specification of Letters Patent. Patented May 23, 1922.

Application filed May 20, 1919, Serial No. 298,407. Renewed October 19, 1921. Serial No. 508,833.

To all whom it may concern:

Be it known that I, RALPH W. ARMSTRONG, a citizen of the United States, and a resident of the city of Westfield, county 5 of Union, and State of New Jersey, have invented certain new and useful Improvements in Cloth Clips, of which the following is a specification.

The invention relates to an improvement 10 in cloth clips of the type which are designed to engage the edge of a cloth, or other flexible fabric, such as the edge of a pocket or the lapel of a coat, for the purpose of securing a watch chain to the cloth, or for the 15 purpose of fastening a display button or fob in position on the cloth.

Most specially defined, the invention relates to that type of fastener which includes a U-shaped body portion designed 20 to receive the edge of the cloth between the legs thereof and which body portion is provided with a spring pressed clamping jaw for engaging the cloth. Such devices now known on the market are commercially 25 defective, among other reasons, due to the fact that the movable jaw is actuated by some form of outwardly swinging clutch member. This outwardly projecting member is quite apt to swing open accidentally 30 thus releasing the clamping jaw and tend in moving about to tear the pocket lining. Such a member is difficult to actuate in that it has to be picked back by the finger nail in order to swing it into its open, inoperative 35 position.

Further with such devices care must be exercised in order to insure the mounting of the clip in position without tearing the cloth and this usually necessitates the use 40 of two hands in order to effect the mounting.

The primary object of the invention is to provide a simple form of device of the class described, which will be free of these 45 objections and at the same time provide a device which can be cheaply constructed.

Another object of the invention is to provide a device of the class described which, when mounted in position, will defeat 50 any attempt to surreptitiously remove the article fastened thereby and, while featuring ease of attachment and demounting from the cloth, will tend to minimize any tendency to accidental displacement.

Various other objects and advantages of 55 the invention will be in part obvious from an inspection of the accompanying drawings and in part will be more fully set forth in the following particular description of one form of mechanism embodying my invention. The invention also consists in certain new and novel features of construction and combination of parts hereinafter set forth and claimed.

In the accompanying drawings:— 65
Figure 1 is a perspective view of a preferred embodiment of my invention with the clasp lever in normal position.

Figure 2 is a view in side elevation of the device shown in Figure 1 mounted in 70 position on a pocket and utilized as a watch chain fastener, and

Figure 3 is a view taken sectionally through the device shown in Figures 1 and 2 and illustrating the method of moving 75 the clamping jaw into an inoperative position.

In the following description and in the claims, parts will be identified by specific names for convenience of expression but 80 they are intended to be as generic in their application to similar parts as the art will permit.

The clip includes a U-shaped body member 10 forming a crotch portion 11 and two 85 jaws 12 and 13 extending from the crotch portion substantially parallel to each other. One of the jaws 12 will be referred to hereinafter specifically as the fixed jaw of the clamping device and the other jaw 13 will 90 be referred to specifically as the lever supporting jaw.

For the purpose of suggesting the use of the device as a mounting for a button, fob or other ornamental effect, the jaw 12 is 95 provided on its outer side with a design 14.

The free end 15 of the jaw 13 is provided with a pair of oppositely disposed inturned fingers 16 constituting a pivotal support for a clasp lever 17, which fingers engage in 100 notches 18 recessed in opposite edges of the clasp lever. The part of the lever which extends inwardly from its pivotal connection constitutes an arm 19 and acts to form the movable jaw of the clasp. This arm 19 105 coacts with the fixed jaw 12 to hold the cloth such as the pocket 20 therebetween. The arm extends inwardly from the free

end 15 of the jaw 13 and forms with the jaw 12 an acute angle, preferably less than 45°. The free inner end 21 of this arm is provided with teeth designed to engage 5 in the cloth. The length of the arm from its pivotal connection to the teeth end has a length materially greater than the shortest distance between the jaws 12 and 13 and engages the cloth at such an angle that any 10 attempt to pull the cloth from the clip will merely result in pulling the arm more firmly into engagement with the cloth and thus press the same into engagement with the fixed jaw 12.

15 The lever includes a finger engaging extension 22 which projects outwardly from the body portion and is preferably angled to bring its lower end 23 outwardly from the jaw 13 as shown more particularly in 20 Figure 2.

Intermediate the arm 19 and the extension 22, the lever is formed into a flat spring bearing portion 24 which portion is engaged continuously by the end 25 of a U- 25 shaped spring 26. This spring is fitted into the body portion, as shown in Fig. 3, and extends through an opening 27 formed in the arm 19, as shown in Fig. 1.

The lower end 23 of the finger engaging 30 extension is provided with an aperture 28 to which may be attached the article to be fastened, such as the watch chain 29, when the device is used as a fastening clamp.

The outer side of the arm 13 is free of 35 projections and provides a smooth finger engaging surface 30 and the finger engaging extension 22 constitutes, in effect, a continuation of this surface so as to permit the operator's finger to slide along the surface 40 30 and engage the extension 22 as shown more particularly in Figure 3.

In mounting the device in position on the cloth, the arm 19 will act somewhat in the nature of a one-way clasp permitting the 45 edge of the cloth to be inserted into position between the free edge of the movable jaw and the inner side of the fixed jaw. While it will be usual, especially where the tooth ends 23 are used, for the operator to move 50 the arm positively into its inoperative position shown in Figure 3, it will be appreciated that this releasing of the movable jaw is not necessary, and the device can be forced into position over the edge of the cloth. During 55 this action the movable jaw will act as a relatively broad guide for engaging the edge of the cloth. The spring acts continuously on the movable jaw thus avoiding any necessity for positively moving the spring into 60 operative position. Should any attempt be made to pull the watch, or other object attached to the chain 29, from the pocket the chain will move into the dotted line position shown in Figure 2 and will thus tend to lift 65 the finger extension 22, forcing the jaw more

positively into its holding engagement with the cloth.

When it is desired to remove the device from its holding position engaging the cloth, the operator engages the device between the 70 thumb and first finger of one hand and by pinching the extension 22 towards the fixed jaw, the movable arm is released from its engagement with the cloth when moved into the position shown in Fig. 3, the device can 75 be readily withdrawn without danger of catching into any internal projections.

By means of a device of the character disclosed, it is possible to avoid any necessity 80 for projections from either side of the U- body portion and the movable jaw can be disposed in inoperative position by a pressing or pinching movement of the operator's fingers in distinction from the usual picking or pulling movement. The utilization of a 85 long movable jaw extending at an angle with reference to the fixed jaw, and extending in the direction of insertion of the edge of the cloth, tends to defeat any tendency for the jaws to be sprung apart when an out- 90 ward pull is exerted on the cloth.

The device can be readily formed from stamped parts and does not require any special machining in its construction.

While I have shown and described, and 95 have pointed out in the annexed claims, certain novel features of my invention, it will be understood that various omissions, substitutions and changes in the form and details of the device illustrated and in its 100 operation may be made by those skilled in the art without departing from the spirit of the invention.

Having thus described my invention, I 105 claim:—

1. A clip comprising a U-shaped member having its two legs spaced apart to receive a pocket edge therebetween, U-shaped lugs extending inwardly from opposite sides of the lower end of one of the legs, and a lever 110 received within and pivoted to said U-shaped lugs.

2. A cloth clip comprising a U-shaped body portion having its two legs spaced apart to receive a pocket edge therebetween, 115 lugs extending inwardly from the lower end of one of the legs, a lever pivoted to said lugs intermediate its ends, the ends of said lever being at an angle to the intermediate portion.

3. A clip comprising a U-shaped body portion having its two legs spaced apart to receive a pocket edge therebetween, a lever pivoted intermediate its ends to the lower end of one of the legs, both ends of said 125 lever being at an angle to the intermediate portion thereof, and means normally retaining the intermediate portion substantially parallel to the legs.

4. A clip comprising a U-shaped member 130

having its two legs parallel and equidistantly spaced at all points, a lever pivoted intermediate its ends to the lower end of one of the legs and normally biased to a position at 5 an angle to the legs, with the upper part of the lever extending across the space between the legs, the lower part of the lever forming

substantially an angular extension of said leg and the intermediate part being substantially parallel to the legs.

Signed at Jersey City, in the county of Hudson and State of New Jersey, this 14th day of May, A. D. 1919.

RALPH W. ARMSTRONG.
